CATHODE-RAY TUBE

Stanley J. Koch, Newark, N. J., assignor to Allen B. Du Mont Laboratories, Inc., Passaic, N. J., a corporation of Delaware

Application November 12, 1940, Serial No. 365,216

7 Claims. (Cl. 250—141)

My invention relates to improvements in cathode-ray tubes of the general type more particularly adapted for television reception, and such as is disclosed in Patent No. 2,186,635 issued January 9, 1940 to Allen B. Du Mont and Alfred J. Hinck, Jr., and Patent No. 2,225,099, issued December 17, 1940, to Peter S. Christaldi.

As a result of development of the so-called Braun tube for television reception, it has been definitely determined that certain values, whether they be of operating potentials on certain electrodes, or of dimensions in the tube structure itself, must be properly correlated in order to obtain the desired operating action. For example, it is known that by increasing the operating potential on an accelerating anode of a conventional cathode-ray tube, the intensity or brightness of the trace or picture is increased. A point or potential range is finally reached, however, whereat the sensitivity of deflection is reduced a prohibitive amount, so that it is not practical to further increase the brightness of the picture by this method alone. Another difficulty has been found to reside in the matter of maintaining the scanning electron ray at a good focus on the fluorescent screen. That is, in making certain changes or variations in some of the operating potentials or in the structure of the tube itself to correct for or improve upon certain operating conditions, the result has been to impair, at the same time, the operating action in other ways, such as by causing some form of distortion of the pattern or by causing some degree of defocusing of the electron ray on the fluorescent screen. Along with this development work, the subject of electron optics has been given considerable attention, in an attempt to formulate some working basis or formulae for use in the most efficient design of cathode-ray tubes for television reception. In putting this theoretical information to practice, however, it has been found that there are still limitations in the way of an occurring decrease in efficiency of operation of the tube in one important sense if certain changes are made to cause an increase in efficiency of operation of the tube in another sense.

Many different types of cathode-ray tubes have been constructed in which there is post-deflection acceleration of the electron beam. In most of these various constructions, however, an elaborate system of electrodes has been necessary which makes these tubes impractical.

A simplified construction or system, employing a single electrode in the form of a ring disposed in proximity to the fluorescent screen, is disclosed in the Patent 2,186,635 referred to above. This novel construction makes feasible commercial production of cathode-ray tubes having the desired operating characteristics referred to.

Heretofore, the importance of electrode position, and size, shape and spacing of the same, have been overlooked in cathode-ray tubes of the prior, general type referred to. As a result, the uses to which such tubes can be put, and the theoretical advantages to be enjoyed with certain types of operation, are sharply curtailed.

In order to gain high intensity, while maintaining high-deflection sensitivity, it is desirable to 10 make as large as possible the ratio of post-acceleration to pre-acceleration potential. It has been found that unless certain designs are applied, defocusing of the fluorescent spot occurs, 15 distorting fields are set up, and it may be impossible to utilize more than thirty percent of the effective fluorescent screen area.

With the foregoing in mind, it is one of the objects of my invention to provide an improved construction of cathode-ray tube of the character referred to in which the operating potentials, and dimensions in the tube structure itself, are such that a picture of the desired brightness 20 on the fluorescent screen can be obtained without necessarily or unduly interfering with the focus or the sensitivity of deflection.

Another object of my invention resides in the provision of an improved construction of cathode-ray tube of the character referred to, which has advantages over those proposed heretofore in the 25 way of a brighter or more intense picture on the fluorescent screen for similar operating conditions, higher picture detail, greater uniformity of the pattern, greater simplicity of construction and of assembly in manufacturing, and more 30 favorable disposition of the various parts and leads with respect to each other to withstand the high differences of potential within the tube.

Another object of my invention resides in the provision of a simplified construction for a cathode-ray tube in which there is post-deflection 35 acceleration of the electron beam or ray, and which overcomes the disadvantages and the limitations of the various designs proposed heretofore.

40 Other objects and advantages will hereinafter appear.

For the purpose of illustrating my invention, an embodiment thereof is shown in the drawings, wherein

45 Figure 1 is an enlarged, fragmentary view taken from Fig. 10, and being partly broken away, partly in elevation, and partly in section, the section being taken on the line 1—1 in Fig. 2;

50 Fig. 1a is a detail, fragmentary view, partly in section and illustrative of a novel step in the assembly of my improved cathode-ray tube, in some cases;

55 Fig. 2 is a view looking toward the right in Fig. 60 1, the electron gun being shown in elevation and

one element thereof being partly broken away to show a detail of the construction;

Figs. 3, 4, 5, 6, 7, 8 and 9 are enlarged, sectional views, the sections being taken, respectively, in the horizontal planes 3—3, 4—4, 5—5, 6—6, 7—7, 8—8 and 9—9 in Figs. 1 and 2; and each being a true projection taken vertically from Fig. 1, but on the enlarged scale;

Fig. 4a is an enlarged, fragmentary, sectional view showing a detail of my improved construction, the section being taken in the horizontal plane 4—4 in Fig. 1;

Fig. 10 is a longitudinal, sectional view of a complete cathode-ray tube constructed and operating in accordance with my invention, the electron gun and associated parts being shown in elevation; and

Fig. 11 is an enlarged view taken from Fig. 1, and showing more clearly the electrodes comprising the electron gun.

The drawings show a cathode-ray tube having a gun construction similar to that described in the patents mentioned above. For convenience of comparison, the various parts have been designated by the same reference characters as the corresponding and respective parts in these prior disclosures.

With reference particularly to Figs. 1, 2, 10 and 11, my improved cathode-ray tube comprises a tube 10 having a bulbous portion 11 on the end wall of which is a fluorescent screen 9. In the neck portion 12 of the tube is the gun for developing the ray of electrons directed at and focused on the screen.

The gun is supported from the stem 15 which is sealed to the open end of the neck 12, and comprises a cathode 16, a modulating electrode 20 in which the cathode 16 is disposed, a first accelerating electrode 22, and a mica disc 24.

The gun comprises further a focusing electrode 29, 29a and a second accelerating electrode 30 provided with the apertured discs 30a and 30b. Deflecting plates 33 are supported by the wires 33a, 33b, 33c and 33d, and a second set of deflecting plates 36 is supported by the wires 36a, 36b, 36c and 36d.

The first or preaccelerating electrode 22 above the modulating electrode 20 is operated at the same voltage as the second accelerating electrode 30. For this purpose, a connection 42 is made from the electrode 30 to the electrode 20. By applying a high voltage to the electrode 22, a brighter spot is obtained, and there is less tendency to defocus during modulation.

In my improved construction, there is a relatively large distance A from the tip 41 of the gun to the adjacent edges 48 of the second set of deflecting plates 36. The relation

$$A = \frac{C}{2.5B}$$

exists approximately, where A is measured in inches, C is the diameter in inches of the fluorescent screen, and B is the distance in inches from the screen to the adjacent edges 49 of the first set of deflecting plates 33. Satisfactory results have been obtained by making A equal to .4 inch with C and B both 14 inches. In the constructions used heretofore, the distance A is much less. By making the distance A greater, and using the relation above expressed, defocusing of the spot during deflection is eliminated. The reason for this is that in my improved construction no appreciable bending or deflection of the beam or ray within the gun structure takes place.

Heretofore it has been generally supposed that no motion or deflection of the ray occurs below the deflecting plates. Actually, this is not true, and the motion of the ray in the gun during deflection has been the cause of poor focusing in the prior constructions.

Important and novel characteristics of my improved tube reside in the provision of the electrodes 58 and 59, which may be in the form of silver coatings on the inside surface of the tube 10, and in the dimensions and relations herein-after specified. By this means, it is possible with my improved tube to obtain a very intense trace or picture by using an extremely high final accelerating voltage, but without, at the same time, reducing the deflection sensitivity by about 50%, when the final accelerating voltage is doubled, for example, as would be the case in the various television receiver tubes used heretofore. The reason for this is that in my improved tube the deflection sensitivity is not an inverse function of final accelerating voltage or potential, as is the case in tubes of the prior art.

In a practical construction of my improved tube, the outside diameter of the neck portion 12 was made 2 1/4 inches, the distance between the edges 59a and 59b of the ring electrode 59 was made two inches, the distance between the edges 59a and 58d was made 1 1/2 inches, and the distance between the edges 58d and 58c was made one inch.

In the case of my improved tube, a potential of say 10,000 volts can be applied to the top electrode 58, 5,000 volts to the electrode 30, and a picture intensity corresponding to 10,000 volts will be obtained accordingly, but instead of cutting down the deflection sensitivity by about 50% as heretofore, it is only reduced by approximately 18% in my tube.

In the sizes of tubes commonly referred to as a "20 inch" tube, and a "14 inch" tube, respectively, the following dimensions, relations and values have been found to give very satisfactory results.

	20 inch tube	14 inch tube
	Inches	Inches
Distance from edges 49 to screen 9 (B)	19 3/4	16 1/2
Mean diameter of electrode 59 (E)	4	3 1/2
Mean diameter of electrode 58	20	13 1/2
Axial length of electrode 58	11	8
Distance from edge 59 to edges 49 (Z)	1	1
Diameter of screen 9	18	11 1/2
Width of ring electrode 59 (Y)	2	7/8

55 In either case, Y may be made equal to Z.

In either case, with E from 2 to 4 inches, Z may be made from 1/2 inch to 1 1/2 inches.

60 The following voltages, measured with respect to cathode, have been found to give satisfactory results for the 14-inch tube.

Cathode (16)	—40 volts
Preaccelerator (22)	+5000 volts
First anode (29, 29a)	+1500 volts
65 Second anode (30)	+5000 volts
Deflection plates	+5000 volts ± respective signal voltages
Electrode 58	+10,000 volts
Electrode 59	+5000 volts

70 The edge 58a of the electrode 58 may be disposed a distance of about an inch from the edge 9a of the screen 9.

It is possible with my improved tube, embodying the structural features and using the rela-

tions and values given above, to employ an extremely high accelerating voltage in order to get a very intense trace or picture, and still deflect the ray to cause the same to scan substantially the entire area of the screen 9, since the deflection sensitivity is only reduced by approximately 18%, as against about 50% reduction in the cathode-ray tubes of the prior art, should the final accelerating voltage be doubled.

It has been found that when the distance from the edges 49 to the edge 59a of electrode 59 is too great, electrostatic fields are set up such that the useful area of screen 9 is reduced as a strong function of the ratio of potentials on electrodes 58 and 59. In addition to the reduction of possible, effective screen area, a radial distortion is introduced, and the outer ends of normally straight lines off the axis are caused to return toward or through the axis of the tube.

On the other hand, when the distance from 49 to 59a is too small, the electrostatic lines of force that would normally terminate in 59 to produce a spherical field within the intervening space, terminate instead on the deflection plates 33 and, to some extent, on the deflection plates 36. As a result, the accelerating field in that space is no longer spherical and produces a distortion of the fluorescent spot. Thus a normally round spot would become elliptical with its major axis parallel to the edges 49.

The electrode 58 may be a coating of colloidal graphite known as "Aquadag" and a terminal coating 58b of silver which contacts or overlaps the "Aquadag" coating at 58c. The electrode 59 is a silver coating.

Spot-welded to the electrode 30 is a metal disc 61 provided with the circular openings shown in Figs. 3 and 4, and with a mica-disc insert 32. The disc 61 acts as a conducting shield for collecting stray electrons which otherwise would form or set up a halo on the screen 9 in the absence or presence of signal voltage. Such a halo, when signal is present, would reduce contrast. The diameter of the shield 61 is relatively large, so that its edge is in close proximity to the wall of the neck of the tube.

A whisker 61a spot-welded to the shield 61 and spring-biased outwardly to cause engagement of its free end with the electrode 59 provides connection between the latter and the shield.

The adjacent ends of ceramic rods 1, 2, 3 and 4 abut the mica disc 32, and are secured to electrode 30 by the straps 30c, 30d, 30e and 30f.

The part 29a of the focusing electrode is secured to the ceramic rods by the straps 29b and 29c (Fig. 6).

The part 29 of the focusing electrode is secured to the ceramic rods by the straps 29d and 29e.

The electrode 22 is secured to the ceramic rods by the straps 22a.

The electrode 20 is secured to the ceramic rods by the straps 20a, 20b and the complementary pieces 20c.

The cathode 16 is supported by a short piece of wire 16a spot-welded to one of the straps 16b secured to the ceramic rods.

The cathode-heater is supported by having its terminals 16e spot-welded to the short pieces 16f of wire which are spot-welded to the respective terminal wires 16' and 16'' extending through the press.

With regard to the supporting wires 33a, 33b, 33c and 33d for the deflecting plates 33, the wires

33a and 33c terminate at the mica disc 32, but the wires 33b and 33d continue through the mica disc 24 to the respective terminal wires 33b' and 33d' which extend through the press.

With regard to the supporting wires 36a, 36b, 36c and 36d for the deflecting plates 36, the wires 36b and 36d terminate at the mica disc 32, but the wire 36a continues to and terminates at the mica disc 24, and the wire 36c extends through disc 24 and is spot-welded to the terminal wire 36c' extending through the press.

An important feature of my improved tube resides in the means for making connection to the intensifier electrode 58. This comprises a coaxial cable made up of a wire 58f extending through a glass tube 58g which is bent as shown, and is provided with an outercoating 58h of silver. As shown in Fig. 10, one end of the wire 58f makes contact with the silver coating 58b. The other end of the wire 58f is spot-welded to a short piece of wire 58k Fig. 8 which is spot-welded to one end of an L-shape piece 58j. The other end of the piece 58j is spot-welded to the terminal wire 58' which extends through the press. The tube 58g extends loosely through the shield 61 and the mica discs 32 and 24, and the silver coating 58h makes electrical contact with the shield 61. When inserting the entire press assembly into the tube blank, the bent glass tube 58g is placed in the position shown in Figs. 1 and 2, so that it clears. The tube 58g is then rotated through 180 degrees and moved axially so that its bifurcated end portion 58i straddles and interlocks with one leg of the L-shape piece 58j, as shown in Fig. 1a and as indicated by dash-line in Fig. 8. When the gun and press assembly are fully inserted into the neck of the tube, therefore, the tube 58g is in the position shown in Fig. 10 and the free end of the wire 58f engages the silver coating 58b.

One end of the connection 42 is spot-welded to the shield 61, and the other end extends through disc 24 and is spot-welded to the wire 22b. One end of the wire 22b is spot-welded to the straps 22a, and the other end is spot-welded to the terminal wire 22' extending through the press.

Connection with the electrode 20 is made by a piece of wire 20d spot-welded to the straps 20a and to the terminal wire 20' extending through the press.

Connection with the cathode 16 is made through a piece of wire 16c spot-welded to the straps 16b and to the terminal wire 16'.

One end of a connecting wire 36x is spot-welded to the wire 36a. The wire 36x passes through the disc 24 and is spot-welded to the terminal wire 36a'.

A connecting wire 29d' is spot-welded to the straps 29c and 29d. The wire 29d' passes through the disc 24 and is spot-welded to the terminal wire 29'.

From the foregoing it will be seen that connection to the intensifier electrode 58 is made by the terminal 58'. Connection to electrode 59, shield 61, and electrodes 30 and 22 is made by the terminal wire 22'. Connection to electrode 20 is made by the terminal wire 20'. Connection to the cathode 16 and one side of the cathode-heater is made by the terminal wire 16', and connection to the other side of the cathode-heater is made by the terminal wire 16''. Connection to electrode 29, 29a is made by the terminal wire 29'. Connection to the plates 33 is made by the terminal wires 33b' and 33d'. Connection to the

plates 36 is made by the terminal wires 36a' and 36c'.

By making connection with the intensifier electrode 58 through the press, by means of the coaxial cable, the old tip or protrusion on the bulb for this purpose is eliminated. Also, all high-tension leads are automatically connected when the bulb is plugged into the socket therefor.

Another important detail of my improved construction resides in the means for assembling and securing together the deflecting plates and the respective supporting wires therefor. For example, and with reference particularly to Figs. 1, 2 and 3, the ends of the wires 36a and 36b for supporting the associated deflection plate are placed against this plate, and upon these ends is placed the strap 36e of sheet metal and having the stamped-out portions shown, to receive these ends. The securing strap lies flush against the deflection plate, and is spot-welded thereto and to the ends of the supporting wires. As shown, the ends of the supporting wires are sandwiched between the deflection plate and the strap 36e, and by reason of the stamped-out portions of the latter, the strap functions as a gauge for quickly and conveniently spacing and positioning the ends of the supporting wires properly and ensuring correct alignment of the parts and uniformity of construction. As shown in the drawings, the other deflection plates and the respective supporting wires therefor are secured together by similar straps, in the same way. Reinforcing pieces, such as 33', join the pairs of adjacent supporting wires for the deflecting plates.

With reference to Figs. 4a and 4b, the wire 36c passes through a grommet 32a having the portions 32c riveted over onto the mica disc 32, and the portions 32e spot-welded to the wire 36c. The distance from the grommet to the edge 32b provides sufficient insulation between the shield 61 and wire 36c. Similar grommets are used for the other wires which pass through or terminate at the mica discs 32 and 24.

It will be understood that various modifications within the conception of those skilled in the art, are possible without departing from the spirit of my invention or the scope of the claims.

I claim as my invention:

1. In a cathode-ray tube, a tube having a screen at the end wall thereof, said tube at the end thereof opposite said screen being provided with a press, a gun supported by said press and disposed in said tube for developing a ray of electrons directed at and focused on said screen, deflecting means for said ray of electrons in said tube, an electrode extending along said tube and beyond said deflecting means in the direction toward said screen, a second electrode disposed between said first-named electrode and said screen for minimizing defocusing of the ray-spot on said screen and for minimizing reduction of deflection sensitivity, said second-named electrode being adapted to operate at a potential higher than the potential of operation of said first-named electrode, and connection means comprising a conductor extending through an elongated insulator having conducting material on the outside thereof, said conductor engaging said second-named electrode and extending along said tube within the same and through said press to provide exteriorly of said tube at said press a terminal for application of potential to said second-named electrode.

2. In a cathode-ray tube, a tube having a screen at the end wall thereof, a gun disposed in said tube for developing a ray of electrons directed at and focused on said screen, a press supporting said gun, means for deflecting said ray to cause the same to scan said screen, an electrode extending along said tube and beyond said deflecting means in the direction toward said screen, a second electrode disposed between said screen and said first-named electrode, said second electrode being adapted to operate at a potential positive with respect to the potential of operation of said first-named electrode, the diameter of said tube at a plane in proximity to said screen being substantially greater than the maximum effective diameter of said screen, and connecting means comprising a conductor extending through an elongated insulator having conducting material on the outside thereof, said conductor extending from said second electrode and along said tube within the same and through said press to provide exteriorly of said tube at said press a terminal for application of potential to said second-named electrode.
3. In a cathode-ray tube, a tube having a screen at the end wall thereof, said tube at the end thereof opposite to said screen being provided with a press, a gun supported by said press and disposed in said tube for developing a ray of electrons directed at and focused on said screen, means for deflecting said ray to cause the same to scan said screen, an electrode extending along said tube and beyond said deflecting means in the direction toward said screen, a second electrode disposed between said first-named electrode and said screen for minimizing defocusing of the ray-spot on said screen and for minimizing reduction of deflection sensitivity, said second-named electrode being adapted to operate at a potential higher than the potential of operation of said first-named electrode, and coaxial-cable means engaging said second-named electrode and extending along said tube within the same and through said press to provide exteriorly of said tube at said press a terminal for application of potential to said second-named electrode.

4. In a cathode-ray tube, a tube provided with screen structure and with a gun for developing a ray of electrons directed at said screen structure, a pair of plates for deflecting said ray, at least one of said plates being supported by wires whose ends are disposed against one side of said plate at an edge thereof and are perpendicular to said edge, and a strap disposed against said ends and flush against said plate at said edge thereof and secured to said plate and said ends, said strap being pressed out to receive and accommodate said ends whereby said strap initially can function as a gauge to space and position said ends with respect to said plate prior to the securing of said parts together.

5. In a cathode-ray tube, a layer of conducting material on the inside of said tube between the gun and screen of said tube, means for supporting an electron gun in said tube, and an elongated insulator carrying an electrical conductor to contact with said layer of conducting material, said insulator and conductor being bent and revolute with respect to said tube to provide contact of said conductor with said layer of insulating material.

6. In a cathode-ray tube, a layer of conducting material on the inside of said tube between the gun and screen of said tube, means for sup-

porting an electron gun in said tube, an electrical conductor to contact with said layer, an insulating supporting member for said conductor, and a conducting electrical shield on a portion of said member to prevent the electric field of said conductor from distorting the electron beam between the gun and the screen.

7. In a cathode-ray tube, a layer of conducting material on the inside of said tube between the gun and screen of said tube, means for sup-

porting an electron gun in said tube, an electrical conductor to contact with said layer, an insulating supporting member for said conductor, and a conducting electrical shield on a portion of said member to prevent the electric field of said conductor from distorting the electron beam between the gun and the screen, said member being bent and revoluble and means to locate and secure said member in its operating position.

STANLEY J. KOCH.
